VAPOR ELECTRIC APPARATUS.

1,110,609.

Specification of Letters Patent. Patented Sept. 15, 1914.

Original application filed December 19, 1905, Serial No. 292,480. Divided and this application filed December 5, 1913, Serial No. 804,820.

To all whom it may concern:

Be it known that I, CHARLES ORME BASTIAN, a subject of the King of Great Britain, and resident of London, England, have invented certain new and useful Improvements in Vapor Electric Apparatus, of which the following is a specification.

This invention has for its object improvements in or relating to vapor electric apparatus, especially lamps of the character known as vapor electric lamps. Such lamps usually comprise a transparent tube with electrodes therein which, in the present instance, are of vaporizable material, such as mercury. The luminous portion of the tube is, according to present custom, denominated as the "burner", and this term is employed in the present specification.

With all classes of mercury vapor lamps or other electric vapor apparatus, it frequently happens that a small quantity of air or other gas remains within the container or occluded in the mercury after the lamp has been sealed, and taken off the pump but according to this part of my present invention I form or arrange in any suitable position on the lamp an enlargement or trap into which the air may be transferred by careful manipulation and retained there by solid mercury which latter may form one of the electrodes, and the air thus trapped is thereby prevented from getting into the arc and disarranging the normal operation of the latter. If the said enlargement or trap be attached to the top of the anode (or cathode) it serves the double purpose of a cushion for the mercury in such electrode forcing the mercury back when the circuit is broken and preventing it from sticking in the tube.

I have illustrated my invention in the accompanying drawing which is a diagrammatic view—in side elevation—partly in section of a burner showing the arrangement for producing the differential heat radiating surfaces at the respective electrodes and varying cross-sectional area of the active electrode surfaces; and for receiving and retaining foreign gases out of the arc stream.

Referring now more particularly to the drawing:—*a* is the container tube which is of small bore (as shown in section) adapted to retain the unvaporized or un-ionized mercury within it by the pressure of the arc

stream and surface tension between said small tube and the mercury or otherwise prevent it passing through the arc path during the operation of the burner. In this burner is shown an enlargement *b* at the negative electrode *b* while the enlargement at the positive electrode merges into the bulb *d* which receives the mercury displaced from the arc stream. In this arrangement this bulb *d* is shown provided with an upwardly extending chamber *i* which is in communication with said chamber *d* and the tube *a*; said chamber *i* being adapted to receive and retain therein any small quantity of air or gas which may be sealed within the burner which device *i* I may conveniently term the air trap.

Any air or gas present at any point in the burner can by shaking or otherwise be removed into this air trap or chamber *i* and thereafter when the burner is in operation and the mercury is forced back into the bulb *d* it will tend to enter said small chamber *i* and will consequently put any such air or gas in said air trap *i* under more or less pressure therein with the result that the return of the mercury from the chamber *d* into the tube *a* (when the burner is returned to its normal position upon discontinuance of current thereto) is facilitated. This air trap *i* may be placed if desired in any other convenient position on the burner *e. g.* it may be arranged at the negative electrode or at both electrodes.

Assuming that the burner is tilted until the mercury from the bulb *d* has filled the small bore tube *a* so as to complete the circuit from *b* to *c* and then the burner restored to the position shown in the drawings or thereabout (by electrically operated mechanism or any other suitable means) and thereby the burner put in operation the action is such that at the starting up of the burner the mercury in the enlargement *d* and the mercury at the negative electrode will be about the level shown.

By the action of the electric current throughout the operation of the apparatus mercury will tend to be transferred from the positive electrode to the negative electrode and consequently the mercury will tend to accumulate at the negative electrode and simultaneously diminish at the positive electrode and as this proceeds eventually the level

of the mercury at the positive electrode will descend in the enlargement *d* and it will be obvious that a very much larger electrode surface is now presented than when said electrode was at the level shown and consequently the active electrode surface is brought so much the nearer to the general body of solid mercury in the bulb *d* and thus an increased cooling effect on the electrode surface is obtained while at the same time the active electrode surface is increased and thereby the heat due to the passage of the current through the mercury at or near this surface is diminished with the result that the temperature of the electrode falls and prevents loss by evaporation or even causes gain by condensation. As the reverse action simultaneously takes place at the other electrode a state of equilibrium is established between the amount of mercury lost and gained by each electrode from whatever cause. It does not follow that this point of equilibrium will be reached exactly at the level of the mercury indicated in the drawing as aforesaid but if the burner be arranged so that the relative cooling effect be increased at one electrode as the mercury is transferred from that electrode then it will automatically arrive at the aforesaid point of equilibrium and thereafter continue so to operate. It will be obvious that if desired and where suitable the current may be passed in reverse direction through the burner illustrated by providing a similar enlargement *c'* at the negative electrode *c* thus enabling the burner to work with the current reversed. Therefore mercury displaced from one electrode owing to the difference in electric potential between the electrodes can be replaced with mercury displaced in the oppo-

site direction owing to the difference in heat potential between the electrodes and by constructing the burner so as to utilize this discovery I am thereby enabled to establish and maintain constant quantities of electrode material at each electrode respectively without the passage of solid mercury through the arc path.

In the following claims the terms "burner" and "mercury" are (for the sake of brevity) respectively used to denote and include any suitable device and any suitable electrode material as hereinbefore defined or explained.

This application is a division of my application Serial Number 292,480, filed December 19th, 1905.

I claim as my invention:

1. In a burner for a vapor electric apparatus, a tube, vaporizable electrodes inclosed therein, means for retaining the vaporizable material during operation, such means consisting of a receptacle, a chamber or space connected with such receptacle and normally sealed by the volatilizable material to form an air-trap.

2. In a burner for a vapor electric apparatus, a tube, vaporizable electrodes inclosed therein, means for retaining the vaporizable material during operation, such means consisting of a receptacle, a chamber or space connected with such receptacle and normally sealed by the mercury to form an air-trap.

Signed at London in the county of London, England this 18th day of November A. D. 1913.

CHARLES ORME BASTIAN.
